COMBINED PEW AND KNEELER

Richard L. Sklaar, 1550 Schuyler Road,
Los Angeles, Calif.

Filed Oct. 5, 1962, Ser. No. 72,007

Term of patent 14 years

(Cl. D15—11)

FIG. 1.

FIG. 2.

FIG. 3.

FIG. 4.

FIG. 5.

FIGURE 1 is a perspective view of a combined pew and kneeler embodying my design wherein the kneeling rail on the right is shown in operating position and the kneeling rail on the left is shown in folded position;

FIGURE 2 is a top plan view of one of the identical kneeling rails, portions of the pew having been omitted for convenience of illustration;

FIGURE 3 is a rear elevational view of the kneeling rail of FIGURE 2;

FIGURE 4 is a side elevational view looking in the direction of the arrows 4-4 of FIGURE 3;

FIGURE 5 is a side elevational view partly in cross section taken about the line 5-5 of FIG. 3.

The dominant features of my design reside in those portions shown in full lines on the drawing.

I claim:

The ornamental design for a combined pew and kneeler, substantially as shown and described.
